NECKTIE

Julián Gutiérrez, Habana, Cuba

Application December 27, 1937, Serial No. 181,885

7 Claims. (Cl. 2—150)

This invention relates to made-up neckties of the four-in-hand type and has for the primary object the provision of a tie of this character which may be easily and quickly applied and removed and adjusted when applied to retain a neat fit with the collar of the wearer.

Another object of the invention is the provision of a tie of the above stated character which embodies a separable neck portion, end portions permanently connected with said neck portion and a knot-forming portion which may be readily adapted to the end portions to secure the latter in proper relation to each other and to bring about cooperation of said end portions with the knot portion to present the tie with the appearance of being hand tied in a four-in-hand fashion.

With these and other objects in view, this invention consists in certain novel features of construction, combination and arrangement of parts to be hereinafter more fully described and claimed.

For a complete understanding of my invention, reference is to be had to the following description and accompanying drawings, in which

25 Figure 1 is a fragmentary perspective view illustrating a necktie constructed in accordance with my invention.

Figure 2 is a fragmentary rear elevation showing the knot portion adapted on the end portions 30 of the tie.

Figure 3 is a fragmentary plan view showing the connection between the neck portion and the end portions.

Figure 4 is a fragmentary rear elevation showing a clamp adapted on the end portions and neck portion where said portions join.

Figure 5 is a fragmentary front elevation showing the clamp applied.

Figure 6 is a fragmentary rear elevation showing the clamp on the tie surrounded by a knot forming portion.

Figure 7 is a sectional view taken on line 7—7 of Figure 2.

Figure 8 is a perspective view illustrating the blank from which the clamp is formed.

Figure 9 is a longitudinal sectional view showing the knot forming portion in full lines prior to being bent and showing in dotted lines the bending of said knot portion.

50 Figure 10 is a fragmentary rear elevation illustrating the tie with a modified form of clamp adapted thereto.

Figure 11 is a rear elevation showing the knot forming portion employed in connection with the

clamp shown in Figure 10 prior to the bending thereof.

Figure 12 is a fragmentary rear elevation showing the modified form of knot forming portion adapted to the clamp shown in Figure 10 prior to the bending of said knot forming portion.

Figure 13 is a fragmentary rear elevation showing the knot forming portion bent into shape and of the type disclosed in Figure 11.

Figure 14 is a perspective view illustrating the blank from which the modified form of clamp is bent from.

Figure 15 is a perspective view showing a plate forming a part of the knot forming portion of the modification shown in Figure 11.

Referring in detail to the drawings, the numeral 1 indicates a fragmentary portion of a made-up necktie of the four-in-hand type and consists of a neck portion 2, knot-forming portion 3 and end portions 4 and 5. The end portions 4 and 5 are stitched or otherwise secured to the neck portion 2, as shown in Figure 3. The width of the end portion 4 is greater than the width of the end portion 5 so as to cover the end portion 5 and to permit folding of a portion thereof about the end portion 5 to give the necktie a tied appearance where it leaves the knot forming portion 3, as clearly shown in Figure 1. The neck portion 2 includes an adjustable elastic portion 6 equipped with a separable fastener 7 to permit the neck portion to be opened and closed.

The knot-forming portion 3 consists of a clamp 8 and a bendable plate 9 provided with a covering 10 of the same material from which the end portions are made. Padding 11 is arranged between the plate and the covering 10 so that said covering will be given a tied appearance. The padding is of the greatest thickness at the center portion thereof and gradually tapers towards its edges, as shown in Figure 9.

The clamp 8 consists of a bendable split band 12, one end of which is provided with a tongue 13 and the other end with a slot 14 to receive said tongue. The band 12 has integral therewith oppositely extending extensions or tongues 15 and also formed on one edge at opposite sides of one of the tongues are teeth 16 adapted to bite into the fabric of the end portions when the band 12 is brought about said end portions and fastened by the tongue 13 being inserted through the slot 14 and bent over, as shown in Figure 5. The band 12 passing about the end portions causes the end portion 4 to curl about the end portion 5 for a limited distance, as shown in Figure 4. The

plate 9 and its covering is then bent about the clamp 8 in a shape to represent a knot of a four-in-hand tie. The tongues are then bent over opposite ends of said plate to prevent shifting thereof on the tie. The plate and its covering adapted to the tie and secured thereon by the clamp cooperates with the end portions, held in proper relation to each other by the clamp, in presenting the tie in tied formation of the four-in-hand fashion.

A necktie made up in the manner described employing the clamp and plate may be readily taken apart to permit the covering of the plate, to be renewed if soiled and also permits easy cleaning or renewal of the end portions if soiled or damaged. The neck portion including the separable fasteners 1 permits said portion to be readily placed about or removed from the neck of a wearer. The neck portion is held tightly on the neck or within the collar of the wearer by the elastic strips so that the knot portion 3 will be retained in proper relation to the collar to give a neat and attractive appearance.

Referring to my modified form of invention as shown in Figures 10 to 15, inclusive, a split band 16 is employed to make up the clamp and has extending from one edge of its plate-like portion an extension 17 and the opposite edges have extending therefrom teeth 18. The ends of the strip portion are detachably connected by the tongue 19 being inserted through the slot 20 and bent over. This type of clamp when applied onto the end portions of the tie fold the end portion 4 properly about the end portion 5 for a limited distance and the teeth 18 thereof bite into the fabric of the end portion 4 with the extension 17 disposed uppermost. A plate 21 is employed in combination with the form of clamp of the modification and has struck therefrom a loop or bracket 22 to receive the extension 17 which after being passed through said bracket may be bent angularly, as shown in Figure 12. The plate 21 is covered with a fabric corresponding to the fabric employed in making the end portions 4 and 5 and after being applied onto the extension 17 is bent about the clamp to present the knot to the tie. The general shape of the plate 21 is slightly different from the plate 9 so that when bent into knot formation will give the knot an appearance of a larger size than that produced by the plate 9.

What is claimed is:

1. A made-up necktie of the four-in-hand type comprising a neck portion, end portions joined to said neck portion, a separable clamp fitted about said end portions to fold one of the end portions about the other end portion for a selected distance, and means forming a knot portion surrounding said clamp with the neck portion and end portions extending outwardly therefrom at opposite ends thereof, and means for detachably securing said means onto said clamp.

2. A made-up necktie of the four-in-hand type comprising a neck portion, end portions joined to said neck portion, a split bendable clamp surrounding said end portions for folding one of the end portions about the other end portion for a selected distance, a bendable plate having a covering of the same material as the material of the end portions and foldable about the clamp to conceal the latter and to present a knot portion having the neck portion and end portions

extending outwardly therefrom at opposite ends thereof.

3. A made-up necktie of the four-in-hand type comprising a neck portion, end portions joined to said neck portion, a split bendable clamp surrounding said end portions for folding one of the end portions about the other end portion for a selected distance, a bendable plate having a covering of the same material as the material of the end portions and foldable about the clamp to conceal the latter and to present a knot portion having the neck portion and end portions extending outwardly therefrom at opposite ends thereof, and means for detachably securing said plate on the clamp.

4. A made-up necktie of the four-in-hand type comprising a neck portion, end portions joined to said neck portion, a split bendable clamp surrounding said end portions for folding one of the end portions about the other end portion for a selected distance, a bendable plate having a covering of the same material as the material of the end portions and foldable about the clamp to conceal the latter and to present a knot portion having the neck portion and end portions extending outwardly therefrom at opposite ends thereof, tongues formed on said clamp and bendable over opposite edges of the plate.

5. A made-up necktie of the four-in-hand type comprising a neck portion, end portions joined to said neck portion, a split bendable clamp surrounding said end portions for folding one of the end portions about the other end portion for a selected distance, a bendable plate having a covering of the same material as the material of the end portions and foldable about the clamp to conceal the latter and to present a knot portion having the neck portion and end portions extending outwardly therefrom at opposite ends thereof, tongues formed on said clamp and bendable over opposite edges of the plate, teeth formed on the clamp to bite into one of the end portions.

6. A made-up necktie of the four-in-hand type comprising a neck portion, end portions secured on said neck portion, a clamp surrounding said end portions to fold one of the end portions about the other end portion for a selected distance, a bendable extension formed on said clamp, a covered plate having a struckout portion to receive said extension and bendable about said clamp to present a knot portion with the neck portion and end portions extending therefrom at opposite ends thereof, said extension being bent angularly after passing through the struckout portion of said plate.

7. A made-up necktie of the four-in-hand type comprising a neck portion, end portions secured on said neck portion, a clamp surrounding said end portions to fold one of the end portions about the other end portion for a selected distance, a bendable extension formed on said clamp, and a covered plate having a struckout portion to receive said extension and bendable about said clamp to present a knot portion with the neck portion and end portions extending therefrom at opposite ends thereof, said extension being bent angularly after passing through the struckout portion of said plate, said neck portion including an elastic strip adjustable as to length and having a separable fastener.

JULIÁN GUTIÉRREZ.
